UNITED STATES PATENT OFFICE.

JOSEPH MATHISON, OF LYNN, MASSACHUSETTS, ASSIGNOR TO HIMSELF AND WILLIAM D. ALLEN, OF SAME PLACE, AND C. B. LANCASTER, OF BOSTON, MASSACHUSETTS.

MACHINE FOR SEWING ON BUTTONS.

SPECIFICATION forming part of Letters Patent No. 268,369, dated November 28, 1882.

Application filed August 1, 1882. (No model.)

To all whom it may concern:

Be it known that I, JOSEPH MATHISON, of Lynn, in the county of Essex and State of Massachusetts, have invented certain Improvements in Machines for Securing Buttons to Material, of which the following is a specification.

This invention has for its object to provide a machine adapted to secure a series of buttons to a boot or shoe or other article by a continuous thread or cord, in such manner that each button will be independently attached, so that if the cord should break or be severed between the buttons the attachment would not be affected.

The invention is intended to provide means for carrying into effect the improved method of attaching buttons described in my application for Letters Patent of the United States filed March 18, 1882, Serial No. 55,723, said method consisting essentially in drawing a primary loop of thread through the material to which the button is to be attached and also through the eye of the button, then drawing a secondary loop through the material and through the primary loop outside of the eye of the button, tightening the primary loop, and finally passing the secondary loop over the button and tightening said loop, thereby interlocking both loops and forming a square knot, one loop or bight of which passes through and the other around the eye of the button.

Of the accompanying drawings, forming a part of this specification, Figure 1 represents a perspective view of a portion of a machine embodying my invention. Figs. 2, 3, 4, 5, and 6 represent similar views, illustrating different stages of the operation. Figs. 7, 8, 9, 10, 11, and 12 represent the position of the button and the loops securing it at different stages of the operation. Fig. 13 represents a side view of the loop-spreaders before they separate to spread and lower the loop. Fig. 14 represents a front view of the same. Fig. 15 represents a front view of the spreaders depressed and separated. Fig. 15^a represents a back view of the same. Fig. 16 represents a section on line x x, Fig. 15. Fig. 16^a represents a side view of the loop-spreaders in position shown in Figs.

15 and 16. Fig. 17 represents a perspective view of the wedge which separates the spreaders. Fig. 18 represents a side elevation of the entire machine. Fig. 19 represents a section on line z z, Fig. 18. Fig. 20 represents an elevation of the opposite side of the machine. Fig. 20^a represents a rear view of a portion of the machine, showing the lower portion of the raceway, supporting standard and its guides. Fig. 21 represents a section on line y y, Fig. 20. Fig. 22 represents a bottom view. Fig. 23 represents a section on line x' x', Fig. 22, and a side elevation of the arm of the machine with its side and parts of its mechanism removed. Fig. 24 represents a section on line y' y', Fig. 22, and a side elevation of the arm of the machine with its side removed. Figs. 24^a, 24^b, 24^c, 24^d, and 24^e represent details. Fig. 25, Sheet 4, represents a section on line z' z', Fig. 22.

The same letters of reference indicate the same parts in all the figures.

In carrying out my invention, I provide a suitable supporting-frame, A, having a narrow elongated work-supporting arm, B, preferably horizontal, and of such size as to enable the upper of a boot or shoe to be drawn upon it, and allow said upper a free movement laterally of the arm. Said arm B is hollow and contains a vibratory thread-carrier, C, and suitable tension devices.

Above the thread-carrier is a needle-plate, D, forming a part of the upper surface of the arm, and provided with a slot, s³, extending longitudinally of the arm, to permit the needle, hereinafter described, to pass downwardly through the needle-plate, and move longitudinally of the arm to feed the material while depressed.

E represents the neck or arm, supporting the needle, presser, and cast-off bars, and located over the work-supporting arm B.

The needle-bar F and cast-off bar G are directly supported in a carrier, H, which is provided with ribs I' I', adapted to reciprocate horizontally in guides or ways I I (see Figs. 24 and 24^a) in the neck E. The carrier H is provided with a substantially-horizontal arm, V,

to the outer end of which is pivoted a lever, W, said lever being pivoted at *a* to the neck E, and provided with a roller, *b*, at its lower end, which bears upon the periphery of a disk, 5 *c*, on the driving-shaft R, said disk having two projecting cams, *e f*. The lever W is held in yielding contact with the periphery of the disk *c* and its cams by a spring, *g*, and is oscillated by said cams and spring, thereby reciprocating the carrier H horizontally, the latter being moved inwardly from the outer end of the neck E by each cam, and outwardly by the spring. The cam *f* is shorter and has less outward projection than the cam *e*, and therefore gives the carrier H an inward movement, which is of 15 less extent and shorter duration than that imparted by the cam *e*. The movements imparted respectively by the cams *f* and *e* to the carrier H, produce what are hereinafter termed 20 "primary" and "secondary" lateral or feed movements of the needle while the latter is in the material.

The needle-bar F is provided with a stud or pin, O, which projects through a vertical slot, 25 P, in the carrier H and enters an orifice, N, in a slide, M, which is fitted in a slot, L, in an oscillating lever, J. Said lever is pivoted at K to the neck, and is oscillated vertically by means of a cam-groove, P', in a disk, Q, on the 30 driving-shaft R, and a connected rod, S, having a stud or roller, T, entering said cam-groove. The connecting-rod S has a slot, U, through which the shaft R passes. The needle-bar F is thus reciprocated vertically, the slide M in 35 the lever J enabling said bar to be reciprocated vertically while at any point to which it is moved laterally.

The cast-off bar G is provided with two projections, *h h*, between which is a stud, *i*, attached to the needle-bar, said stud having a considerable independent movement between the projections *h h*, so that as the needle-bar rises and falls the stud *i* moves the cast off bar to a limited extent in the same directions, the 45 movements thus imparted causing the cast-off to be operated in the usual manner in casting off the primary loop, as hereinafter described; but, as it is necessary to give the cast-off an independent downward movement while the needle is depressed and moving laterally during 50 the secondary feed movement, before alluded to, I provide at the top of the neck E a bell-crank lever, *a*³, pivoted to an arm on the neck, and so located that when the needle-bar is making 55 its secondary or longer feed movement the upper end of said bar will strike a projection, *a*⁵, on one arm of the lever *a*³, as shown in Fig. 24^a, and turn said lever on its pivot, thereby pressing its other arm, which has a projection, 60 *a*⁷, downwardly on a pin or stud, *a*⁶, on the cast-off bar, and depressing the latter, as shown in Fig. 24^b, just before the needle-bar rises at the completion of the outward or feed movement.

The presser-bar *j* is provided with an elongated presser-foot, *k*, composed of two arms, 2 65 3, connected by a block or enlargement, *u*³, to

which the presser-bar is attached, and separated by a slot, *l*, extending longitudinally of the work-supporting arm and coinciding with the slot *s*³ in the needle-plate D. The sides of 70 the slot *l* are formed to support the head of the button *x*, of the kind shown, in an upright position with its edge or shank projecting downwardly into said slot, so that when the secondary loop is pulled in, as hereinafter described, it will necessarily inclose the shank 75 of the button.

The work-holding arms or branches 2 3 are curved upwardly at their rear ends, and the curved portions are separated from each other by a much wider space than the slot *l*, so that the attached button can pass freely back from the presser-foot, either in the direction of the length of the work-supporting arm or diagonally. This arrangement enables a shoe-upper, 85 to which the buttons are attached in a curved row, to be freely fed along without obstruction of the attached buttons by the presser-foot, said buttons moving diagonally back from the presser-foot. The presser-bar is raised to permit the work to be fed by the lateral movements of the needle by a bell-crank lever, *m*, pivoted at *n* to the neck E, and connected by a rod, *o*, to a lever, *p*, which is pivoted at *a*, and has a roller, *r*, bearing on the periphery 95 of the disk Q on the shaft R, said disk having the cam-groove *p'* in its side.

The disk Q has two cam-projections, *t t*, which act alternately on the roller *r*, and swing the lever *p* in the direction required to raise 100 the presser-bar. A spring, *u*, on the outside of the neck E, bearing on a stud, *v*, projecting from the presser-bar, presses downwardly on said bar and the presser-foot, and forces the latter down upon the work when the cam *t* ceases to act on the lever *p*.

A hand-lever, *w*⁴, is pivoted to the outer surface of the neck E, to enable the operator to raise the presser-foot independently. The presser-foot is provided at its upper end with 110 an enlargement, *w*³, having ears *a'* *a'*, in which is journaled a rod or arbor, *b'*, having between the ears *a'* *a'* an enlargement or collar, *c'*, rigidly secured to said rod or arbor.

d' d' represent arms pivoted at *e' e'* to the 115 collar *c'*, and adapted to swing on their pivots toward and from each other. These arms, which I term "loop-spreaders," are provided at their swinging ends with hooks *f' f'*, and on their front sides with spring-fingers *g' g'*, said 120 hooks and fingers co-operating in grasping a loop of thread, as hereinafter described.

h' represents an arm journaled on the rod *b'*, so as to turn independently thereon, and provided with a curved wedge, *i'*, adapted to 125 be inserted between the spreaders *d'* and separate the same, as shown in Figs. 1, 3, 15, and 16. The collar *c'* is cut away or slotted centrally to receive the arm *h'*, and the slot terminates at one side of said arm in a shoulder, *k'*, 130 adapted to bear against a corresponding shoulder, *j'*, formed on the arm.

The rod b' is provided with an arm, l' , connected by means of an adjustable trunnion, m' , with an adjustable socketed ear, n' , on a rod, o' , which extends backwardly and is pivoted 5 to a lever, p' , the latter being pivoted at q' to the frame A, and provided with a roller, r' , entering a cam-groove, s' , in a disk, t' , on the driving-shaft.

The rod b' is oscillated by means of the cam-groove s' and the intermediate devices, the cam-groove being formed, as shown, to give the rod the following movements, viz: The spreaders being directly under the collar to which they are pivoted, as shown in Figs. 1, 3, 15, and 16, 15 and being held apart from each other by the wedge i' , the spreaders are next moved forward, leaving the wedge, which is held in the position shown by a spring, u' , which holds a leather buffer, v' , on the arm h' against the bottom of the enlargement u^3 of the presser-bar. Each spreader is provided with a spring, a^2 , which is secured at one end to the block c' and at the other end to the spreader, as shown in Fig. 15^a, and presses the spreader inwardly, so that as the spreaders pass forward beyond the wedge and upward they close inwardly, as shown in Figs. 13 and 14. Before the spreaders complete their forward movement the shoulder k' on the collar c' comes in contact with the shoulder j' on the wedge-arm h' , and causes the wedge to move forward with the spreaders, the latter remaining closed, however, in advance of the wedge. When the wedge is thus moved forward a spring-dog, b^2 , 35 pivoted to an extension of the enlargement of the presser-foot, engages automatically with a tooth, c^2 , on the rear portion of the wedge, as shown in Fig. 13, and locks the wedge in the position shown, so that it is ready to separate the spreaders on their return or downward movement. The spreaders having entered a loop of thread, as hereinabove described, are next moved backwardly and downwardly, and during said movement are separated by the 40 wedge, as shown in Figs. 1, 2, 15, and 16. When the spreaders have nearly completed their downward movement an arm, d^2 , attached to the collar c' , strikes a lateral projection on the dog b^2 , as shown in Fig. 16^a, and disengages the dog from the tooth of the wedge, the latter, under the influence of the spring u' , resuming its original position. (Shown in Figs. 16 and 16^a.)

The time of the described movements of the spreaders with relation to the movements of the needle is more particularly described in the general operation of the machine.

f^2 represents the button-reservoir, and g^2 the inclined raceway leading therefrom. The raceway is curved inwardly at its lower end, and is given a quarter-twist, so as to present the eyes of the buttons sidewise to the needle, as shown in Fig. 1. The raceway is formed to permit the buttons to be drawn from its end, 65 instead of being drawn out laterally, as in my Patent No. 252,117, dated January 10, 1882.

The lower end of the raceway is provided with a yielding spring, w , which projects partly across the raceway, and bears against the lower buttons, and constitutes a yielding stop, 70 holding each button therein in succession until said button is withdrawn from the raceway, as described hereinafter. The raceway is supported with the reservoir on a post composed of two sections, h^2 and i^2 . The lower end of the section h^2 , to which the reservoir and raceway are directly attached, is journaled on the section i^2 , which is adapted to slide horizontally in guides j^2 on the frame A. The raceway is therefore adapted to oscillate laterally of the work-supporting arm and to reciprocate longitudinally thereof. The pivoted section h^2 is provided with an arm, j^3 , having a screw, k^2 , on its outer end bearing against the side of the neck E. The neck is 80 provided with an inclined or diagonal surface, l^2 , over which the screw k^2 passes when the raceway is moved longitudinally. A spring, m^2 , extending from a stud on the section h^2 to a stud on the section i^2 , draws the raceway 90 inwardly toward the neck E. When the raceway is moving backwardly from the outer end of the work-supporting arm its screw k^2 , in passing over the diagonal surface l^2 , is forced outwardly, thereby swinging the raceway outwardly. The swinging and longitudinal movements of the raceway cause the delivering or lower end of the raceway to move diagonally from the position it occupies when presenting a button to the needle, as shown in Fig. 1, to 100 the position it occupies after the button has been withdrawn from the raceway, as shown in Figs. 4 and 5. The sectional post h^2 i^2 is reciprocated in its guides by means of a lever, o^2 , pivoted at p^2 to the frame A, engaged at 105 its lower end by a roller with a cam-groove, r^2 , in a disk, s^2 , on the driving-shaft, and at its upper end with a block, t^2 , pivoted to the section i^2 , the upper end of the lever being bifurcated to embrace the block t^2 . 110

The thread-carrier, which operates in the usual manner, is supported in a vertical rock-shaft, u^2 , having an arm, v^2 , which is connected by a rod, w^2 , with a lever, x^2 , which is pivoted at y^2 to the frame A, and has a roller engaged 115 with a cam-groove, z^2 , in the disk c on the driving-shaft, said devices oscillating the carrier and causing it to alternately hold the thread away from and press it against the hook side of the needle. 120

Operation: The button-raceway being in position, as shown in Fig. 1, the eye of the lower button, x , is held under the needle. The needle descends through the eye of the button, the material, and the needle-plate. The needle then makes its shorter or primary feed movement while down. At the same time the thread-guide swings around to press the thread against the hook side of the needle. The needle is then raised and draws a primary loop, 125 C' , through the eye of the button, as shown in Fig. 3. Then the needle is moved back to its 130

first position, passes down through the first loop, as seen in Fig. 4, outside the eye of the button, through the material and the needle-plate. While the hook of the needle is perforating the material the raceway is moved backwardly, and the loop C' is then caused to pull the last button past the yielding spring w and out of the raceway, as shown in Fig. 4. The needle then makes its longer or secondary feed movement, and the thread-guide again moves to press the thread against the hook of the needle. While the needle is making its secondary feed movement the cast-off is moved down to the material by the arm a³ and casts off the loop C'. The needle rises, and as it rises draws up a secondary loop, D', through the first loop, as shown in Fig. 5. The operation of drawing the secondary loop entirely up tightens the primary loop, as shown in Figs. 6 and 9. The needle then drops enough to free the hook from the cast-off, so as to release the loop from the hook of the needle. The spreaders swing toward the needle at the same time, and the hooks of the spreaders, which are now close together, enter the loop as soon as the loop is released from the hook of the needle. The forward swinging movement of the spreaders after the hooks enter the loop is sufficient to deflect or bend the loop away from the needle. The spreaders then commence to recede from the needle, and at the same time are separated at their hooked ends, thus spreading the loop into a triangular form, and carrying it over the head of the button, as shown in Figs. 1 and 10. The springs g' serve to hold the loop upon the hooks during their receding and separating movements. While the loop D' is being opened and carried over the head of the button the needle is moved to its original position, and at the same time the raceway returns to its original position, so as to present its lower button to the needle. The needle then descends through the eye of the lower button in the raceway, engages with the thread, which is again presented to it by the thread-carrier, and draws up another primary loop through the eye of said lower button. The operation of drawing up the last-named loop draws in the secondary loop previously drawn over the preceding button, drawing said loop inwardly and interlocking it with the primary loop of said button, thus forming the square knot which secures the button to the material, as shown in Fig. 11. The above-described steps are taken in the attachment of each button. c³ represents a bent arm, which is pivoted to the extension of the upper part of the presser-foot, and is held by a spring, d³, against an adjustable stud, e³, on the rod o'. One end of said arm c³ projects in front of the spreaders, and is raised and lowered by the action of the rod o' and spring d³. The arm c³ is brought down upon the secondary loop while said loop is in the position shown in Fig. 1, and prevents the loop from rising and failing to be

drawn under the button when it is tightened by the operation of drawing up the succeeding primary loop, as above described, in case the springs g' g' release the loop before it is tightened or if from any cause the loop has a tendency to rise above the button it is intended to aid in securing. 70

I do not limit myself to the employment of the arm a³, however, as it is only intended as 75 an auxiliary device to guard against the accidental loosening of the loop.

I do not limit myself to the particular devices shown for forming the knot which attaches the buttons, as said devices may be variously modified without departing from the spirit of my invention. 80

The cams e f, which impart the primary and secondary feed movements to the needle, are made adjustable as to their projection from 85 the periphery of the disk c, to which they are attached, so that the length of said feed movements, or either of them can be varied, as may be desired. To this end each of said cams is attached to the disk c by screws s⁴ s⁴, the 90 heads of which are countersunk in the outer surfaces of the cams and screws s⁵ s⁵, whose heads are provided with flanges countersunk in the inner surfaces of said cams, as shown in Fig. 24. The screws s⁴ hold the cams to 95 the disk, and the screws s⁵ regulate the approach of the cams to their seats on the disk, the cams being movable toward and from the disk. 100

I claim—

1. In a machine for attaching buttons, the combination of button-feeding mechanism, and mechanism for first drawing a primary loop of thread through the material and the eye of a button; secondly, drawing a secondary loop 105 through the material and through the primary loop outside of the eye of the button; thirdly, throwing the secondary loop over the head of the button and finally forming said loops into a square-knot, as set forth. 110

2. In a machine for attaching buttons, the combination of loop-forming mechanism, button-feeding mechanism whereby a button is presented to the needle of the loop-forming mechanism, means for imparting to said needle 115 the primary and secondary feed movements described, whereby first the primary and secondary loops are drawn respectively through and outside of the eye of the button, and, secondly, the material with the partially-attached 120 button is advanced, and devices for spreading and depressing the secondary loop after the material is advanced, to cause said loop to inclose the button and hold it until tightened by the subsequent action of the loop-forming 125 mechanism, as set forth.

3. In a machine for attaching buttons, the combination of button-feeding mechanism, a longitudinally-slotted presser-foot, a loop-forming mechanism, means for imparting to 130 the needle and cast-off of the loop-forming mechanism the primary and secondary lateral

movements described, means, substantially as described, for vertically reciprocating the cast-off at different points in its lateral movements, and loop-spreading devices, all arranged and 5 operated substantially as described.

4. The presser-foot composed of two connected arms separated by a longitudinal slot, the sides of which are adapted to support a button and having an enlarged rear opening 10 to permit the passage of an attached button, as set forth.

5. The combination, with the button-feeding and loop-forming mechanism, of the loop-spreader and mechanism for inserting said 15 spreaders into the secondary loop and depressing and separating them to depress and spread said loop, as set forth.

6. The combination of the rod b' , having an enlargement or collar, mechanism for oscillating the same, the spreaders pivoted to said collar and pressed inwardly by springs, the wedge i' , journaled on the rod, and drawn backwardly by a spring, u' , the shoulders $j' k'$, arranged as described, whereby the spreaders 25 are moved forward and in advance of the wedge, and the latter is subsequently moved with the spreaders, a dog, b^2 , to lock the wedge, and an arm, d^2 , to disengage the dog from the wedge when the spreaders move backwardly, as set forth.

7. The combination, with the loop-spreader, of the auxiliary loop-holding arm and mechanism for raising and lowering the same, as set forth.

8. The raceway pivoted to a longitudinally-movable support, i^2 , combined with means for oscillating the raceway and moving it longitudinally, as set forth.

9. The combination of the raceway, the section h^2 , supporting the raceway, the longitudinally-movable section i^2 , having a pivotal connection with the section h^2 , mechanism, substantially as described, for reciprocating the section i^2 and the parts supported thereby, 40 and the fixed incline l^2 , the arm or device k^2 on the section h^2 , bearing against said incline, and the spring m^2 , whereby the raceway is oscillated when moved longitudinally, as set forth.

10. The combination, with the needle and cast-off bars, of the carrier H , guiding said bars and horizontally movable in fixed guides, means for giving said carrier first a short and then a longer reciprocating movement, mechanism, substantially as described, for reciprocating the needle-bar vertically, devices on the 55 needle and cast-off bars causing the operation

of the latter by the vertical movements of the needle-bar, and an independent device operated by the longer lateral movement of the needle-bar to depress the cast-off bar, as set forth.

11. The combination of the carrier H , reciprocated horizontally, as described, the needle and cast-off bars guided and moved laterally 60 by the carrier, the oscillating lever J , having a slot, L , a slide, M , in said slot engaged with a stud on the needle-bar, the projections $h h$ on the cast-off bar, and the interposed stud on the needle-bar, whereby the cast-off is operated during the vertical movements of the needle-bar, and the lever a^3 , pivoted to a fixed support and operated by the longer lateral movement of the needle-bar, to depress the cast-off, 75 as set forth.

12. The raceway formed to permit the removal of the buttons from its end and adapted to be moved longitudinally and laterally, as described, combined with the spring w , projecting partly across the end of the raceway 80 and adapted to hold the lower button with a yielding pressure, as set forth.

13. The combination, with the loop-forming mechanism, of the movable raceway adapted to present the eye of the last button it contains to the needle, and to hold the button while a loop is being drawn through the eye thereof by the needle, and mechanism for moving the raceway backwardly while the said loop is held by the needle, thereby withdrawing the button from the raceway, as set forth.

14. In a machine for securing buttons, the combination, with the loop-forming and feeding mechanism, of the narrow elongated work-supporting arm adapted to permit the free 95 lateral and longitudinal movement of a boot or shoe upper, and the presser-foot having a slot adapted to support a button while it is being attached, and an enlarged rear opening to permit the passage of the attached buttons, 100 as set forth.

15. The combination, with the laterally-movable needle, of the cams $e f$, and intermediate devices for moving the needle laterally, said cams being adjustable so as to regulate the 105 feed movements of the needle, as set forth.

In testimony whereof I have signed my name to this specification, in the presence of two subscribing witnesses, this 29th day of July, 1882.

JOSEPH MATHISON.
